UNITED STATES PATENT OFFICE.

IRVIN H. WILLIAMS, OF RICHMOND, VIRGINIA.

SLING.

Application filed April 16, 1924. Serial No. 706,887.

To all whom it may concern:

Be it known that I, IRVIN H. WILLIAMS, a citizen of the United States, residing at the city of Richmond, in the State of Virginia, have invented certain new and useful Improvements in Slings, of which the following is a specification, reference being had therein to the accompanying drawing.

My invention relates to slings for lifting, carrying and transporting heavy and cumbersome objects in factories and warehouses; such slings being suspended from cranes, overhead trolleys, and the like.

My invention has for its object the provision of means for safely, expeditiously, and economically handling heavy cylindrical, rounded, or flat objects; and in particular barrels and hogsheads, especially those which are of irregular shape and light construction, and in which such materials as cement, or tobacco, are shipped in bulk.

Taking the tobacco hogshead, for instance: this class of container is irregular in shape, is not truly cylindrical, is of comparatively flimsy construction, can be rolled only with effort, and when loaded is very heavy. The weight of a filled tobacco hogshead ranges from nine hundred pounds to twenty four hundred pounds, according to the density to which the tobacco has been prized. To lift such a hogshead from the floor, or to roll it over any thick or high object such as a heavy chain or piece of angle iron, by simple man power, is impracticable. Tongs or dogs are not well suited to lifting such loads, since the strength of the container is not sufficient to allow lifting by such means without some danger to the handlers.

Furthermore, to conserve space in tobacco warehouses the hogsheads must be stacked. The use of the ordinary chain sling is attended by loss of much time in properly adjusting the sling, and also by danger to the handlers when removing the chain from the stacked hogshead. In some cases hogsheads are stacked by rolling them up planks to the top of the first tier; a difficult and laborious operation, and one in which much time is lost. Manifestly, it is still more difficult and laborious to roll hogsheads from the floor to third and fourth tiers.

By the use of my improved sling the warehouse hands can handle hogsheads and other heavy loads with economy, and with-

out danger; and stacking can be easily accomplished to any reasonable height.

In the drawing, which forms a part of this specification, and in which like numerals refer to like parts:

Figure I shows my sling in perspective; Figure II shows the sling in end elevation, and supporting a hogshead above the floor level; and Figure III shows one way in which the sling may be used for stacking.

Referring to Figure I: 1 and 2 are triangular frames of structural steel, each suspended from a beam 3, to which is secured a plate 4 provided with an opening 5 for crane or trolley hook. The upstanding legs 6 of frame 1 are connected at their lower ends to the angle 7, reenforced by gusset plates 8. Similarly the legs 9 of the frame 2 are connected to the angle 10 reenforced by the gusset plates 11.

Secured to corresponding ends of the angles 7 and 10, and underneath them, are the thin flat bars, 12 12. In the drawing these bars appear to be of considerable thickness, shown so to obtain clearness of detail; but in practice they are made so thin that they will yield to the pressure of the weight carried and conform somewhat to its shape. When the load is applied on the bars they are deflected, and their ends, and consequently the lower ends of the frames 1 and 2, are drawn towards one another. This is possible by virtue of the elasticity of the end frames. This elasticity of the end frames and the elasticity of the flat bars enables the latter to conform somewhat to the shape of the load, holding it more securely, and making it much less liable to roll or shift its position accidentally.

In Figure II a hogshead is shown carried in the sling. When about to lift a hogshead from the floor, the sling is lowered nearby, until it rests upon the two flat bars 12, 12. The hogshead is then easily rolled over the adjacent flat bar, and until it stands between the two bars. Upon the sling being raised by the hoist, the hogshead will find its own seat on the two bars, which, as explained above, will deflect and adapt themselves more or less to the contour of the load.

In Figure III I show a method of stacking barrels or hogsheads by means of my improved sling. The numeral 13 indicates

the first row of hogsheads; the numeral 14 the second row; and the numeral 15 a third row; and so on. The second row is being extended. A "horse" 16 is set in the ware-
 5 house aisle, and opposite to the end of the row 13. Stout planks 17 are placed upon the horse and upon the first row of hogs-
 heads, to form a platform. The loaded
 10 sling (Figure II) is brought over the planks 17; and it is lowered until the bars 12 are seated on the said planks 17. The hogshead 18 is then easily rolled out of the sling, and along the planks, until it is dropped off their ends into a resting place between the two
 15 nearest hogsheads in the first row. As the hogsheads are placed, the planks are drawn back to uncover the next "seat".

To place the third row, or the fourth row, a horse of the requisite height is placed in
 20 position, and from it planks are run to the last row of hogsheads. The stacking pro-
 ceeds as before.

I do not confine myself to the use of an elastic structure, for my sling would be of
 25 great use even if its several members were rigid. The essential feature of my invention is the spaced apart thin bars 12, 12; and they are supported by a framework
 30 preferably built of steel or iron, and which is consequently more or less flexible and elastic. This flexibility and elasticity adds to the usefulness of my invention.

I claim:

1. A sling adapted to carry a load, having
 35 two flat members spaced apart and substan-
 tially parallel to one another to form a
 cradle to carry the load, with cross members
 secured to each end of the flat members to
 40 hold them in their spaced relation, and
 forming with the flat members an open
 frame of substantially rectangular shape,
 and having means secured to the frame by
 which it may be suspended in a substantially
 45 horizontal plane.

2. A sling adapted to carry a load having
 curved surfaces, and consisting of two flat
 and extended members parallel to one an-
 other with two cross members secured to the
 50 adjacent ends of the extended members and
 forming with them a rectangular and open
 frame to cradle the load; with means at-
 tached to the corners of the frame for sup-
 porting it from the hoist.

3. A sling adapted to carry a load having
 55 curved surfaces, and consisting of two elas-
 tic and extended members parallel to one
 another and adapted to embrace and sup-
 port the load, also cross members secured

to the ends of the extended members to hold
 the two extended members at the desired
 60 distance apart, and means attached to the
 ends of the cross members by which the
 cradle formed by the extended members and
 the cross members may be lifted from the
 65 ground.

4. A sling consisting of two elastic par-
 allel members held in spaced relation to one
 another by cross members to form a cradle
 to support irregularly surfaced loads; and
 means for raising and lowering the cradle.
 70

5. A sling consisting of two elastic
 horizontally disposed supporting members
 spaced apart to form a cradle adapted to
 embrace and support a load, a framework
 adapted to hold the supporting members in
 75 spaced relation and to connect the support-
 ing members with the hoisting means, the
 said framework being also adapted to allow
 the supporting members to embrace the load
 upon receiving its weight.
 80

6. A sling consisting of an open horizon-
 tally disposed rectangular framework, hav-
 ing two sides formed of thin flat bars longer
 than the load it is designed to carry; also
 two more rigid sides to hold the longer
 85 sides in spaced relation and at a distance
 apart somewhat less than the width of the
 load, the said longer sides being attached
 to the more rigid sides in such a manner that
 when the frame is lowered the longer sides
 90 will lie substantially flat upon the ground,
 so that a heavy load may be rolled over one
 of the longer sides to a position between the
 two longer sides; and a vertically disposed
 frame attaching the horizontally disposed
 95 frame to the hoisting means; the vertically
 disposed frame being adapted when the load
 carrying horizontal frame is lifted from the
 ground to allow the said thin flat bars to
 embrace and support the load.
 100

7. A sling consisting of two flat elastic
 bars longer than the load to be carried at-
 tached to the under sides of two less elastic
 spacing bars to hold the flat bars in relation
 to one another and at a distance apart some-
 105 what less than the width of the load; the
 flat bars and the spacing bars being so dis-
 posed relatively to one another that when
 the sling is lowered the flat bars may be low-
 ered flat upon the ground; and means for
 110 suspending the load carrying bars from the
 hoisting means.

In testimony whereof I have hereunto
 affixed my signature.

IRVIN H. WILLIAMS.
